UNITED STATES PATENT OFFICE.

WILLIAM B. REYNOLDS, OF ROUNDUP, MONTANA.

SELF-DUMPING MINE CAGE.

1,410,124.

Specification of Letters Patent. Patented Mar. 21, 1922.

Application filed October 9, 1920. Serial No. 415,757.

To all whom it may concern:

Be it known that I, WILLIAM B. REYNOLDS, a citizen of the United States, residing at Roundup, in the county of Musselshell and State of Montana, have invented certain new and useful Improvements in Self-Dumping Mine Cages, of which the following is a specification.

The object of my said invention is to provide means in connection with a hoisting cage for a mine for the purpose of dumping loaded cars being raised by said hoisting cage when a predetermined level has been reached, the operations of dumping and re-storing the car to original position being effected automatically, all as will be hereinafter more fully described and claimed.

Another object is to adapt the cage for carrying men, mules, supplies, etc., where dumping is undesirable or unnecessary.

Referring to the accompanying drawings which are made a part hereof and on which similar reference characters indicate similar parts,

25 Figure 1 is a view showing a mine hoisting cage constructed in accordance with my said invention with a loaded car thereon, normal position being shown in whole lines and the position which the parts occupy 30 when dumped, in dotted lines,

Figure 2, a view looking at the same parts toward the front end of the car, and

Figure 3, a section on line 3—3 of Figure 2.

35 In said drawings the portions marked A represent the track or timbers on which the mine cage runs, B the frame of the mine cage, and C the car.

These several parts are in themselves of 40 a construction and arrangement substantially like what is in ordinary use or may be of any appropriate construction and arrangement. The hoisting cage B is connected at 10 to any hoisting means operated by any appropriate hoisting power.

45 The cage B carries a main platform comprising fixed side members 10 and a swinging trap or platform 11 hinged to the fixed members at 12 and carrying rails 13 for the 50 car C adapted to connect with the track system of a mine so that the car may be run on and off the cage as desired. The car itself is preferably of the type shown in my Patent No. 1,327,255, Jan. 6, 1920, known 55 as the "Reynolds automatic mine car" and needs no specific description here. It has a

movable bottom portion hinged at one end and adapted to follow the movable platform 11 down and up.

The side sills of platform 11 have downwardly projecting portions 14 which are provided with lower inclined faces 15 and 16 sloping down from the front ends of the sills and separated by points 17, and the face 16 terminating in a stop 18. Diagonal 60 supporting rods 19 pivoted at 20, are provided with rollers 21 at their lower ends supported by a shaft 22 held in blocks 23 at the lower ends of bars 19. Rollers 21 extend under sill extensions 14, and are 65 normally held in position in front of points 17 as shown in Figure 1 by the cam action of faces 15. Rods 19 pass between rollers 24, 24 on longitudinal extending bars 25, 70 guided between fixed bars 26, 26. 75

At one end of each bar 25 is a roller 27 adapted to bear on a cam 28 and at the other end the bar is reduced to a point 29 adapted to bear on a positioning roller 30.

When the movable platform is lowered to 80 dump the car it is supported at its forward end by a cross bar 31 between two yokes 32 forming a portion of cage B.

On the fixed platform members 10 are provided supports 33 for the body of the 85 car to hold the same up when the bottom is lowered for dumping. Latches 34 are pivoted on the supports to engage the car at each end and hold it in place on the rails 13. When the car is to be run off the cage 90 the latches at one end of the car will be lifted out of the way.

My improved mine cage is also adapted for use in transporting men, mules, supplies, etc., and for this purpose I have provided 95 leaves 35 hinged at 36 to the side members of the cage. The car C being removed, leaves 35 will be lowered to the dotted line position, and end members 37 will be inserted in grooved guides 38 attached to the 100 uprights of the cage. Thus I transform my self-dumping cage and car into a non-dumping device for special uses such as those indicated.

In operation, when my car is lowered, 105 cams 28 will move bars 25 to the right (Fig. 1) whereupon rollers 24 swing bars 19 to ride away from stop 18 along cam-face 16 gradually lifting the trap and attached parts and when the rollers pass point 110 17 and ride against faces 15 the trap is practically locked in place. On the return

trip, the parts remain as described until point 29 strikes roller 30 when the trap is quickly lowered by a reverse operation of the parts enumerated, which assume the 5 dotted line position (Fig. 1). The coal or other material slides gently but quickly out of and away from the car, which is then ready to repeat the operation.

My invention is not limited to the embodiment shown since various modifications 10 will readily occur to those skilled in the art. The true scope thereof is indicated by the appended claims.

Having thus fully described my said invention, what I claim as new and desire to 15 secure by Letters Patent, is:

1. A hoisting cage for mines comprising a hinged platform, a roller support for said platform, and means for tripping said support at a predetermined point, substantially 20 as set forth.

2. A hoisting cage for mines comprising a hinged platform having sills with cam shaped lower edges, a swinging support 25 adapted to run upon said lower edges, and means for operating said swinging support back and forth to control the position of said sills, substantially as set forth.

3. A hoisting cage for mines comprising 30 a hinged platform, a dumping car thereon with a hinged bottom, supports to maintain the body of the car in horizontal position, and means for tripping said platform and dumping the car at a predetermined point, 35 substantially as set forth.

4. A hoisting cage for mines comprising a hinged platform adapted to carry and support a car with a hinged bottom mounted on said platform, means for supporting the 40 body of the car in a horizontal position above said platform, a support for said platform, and means for tripping said support to permit said platform to fall and the car to dump at a predetermined point, substantially 45 as set forth.

5. A hoisting cage for mines comprising a hinged platform adapted to carry and support a car with a hinged bottom mounted on 50 said platform, means for supporting the body of the car in a horizontal position above said platform, a support for said platform, and means for tripping said support to permit said platform to fall and the car to dump at a predetermined point, and 55 means carried by the cage for supporting the platform at its free end when in lowered position, substantially as set forth.

6. A hoisting cage for mines comprising a frame, a platform hinged at one end 60 therein, a movable support for the other end of said platform, a trip positioned alongside said cage, means for contacting with said trip to throw the support in one direction to permit the platform to fall, and other 65 means for contacting with said trip to throw

the support in the opposite direction to elevate the platform to horizontal position, substantially as set forth.

7. A hoisting cage for mines comprising a frame, a hinged platform, hinged supports for said platform extending normally in a diagonal direction across said frame and engaging under the front end of said platform, means for throwing said hinged supports backward upon their hinges at a predetermined point to permit the front end of said platform to fall, and means for returning said hinged supports to their normal position to restore said platform, substantially as set forth. 70 75 80

8. In a hoisting cage for mines, the combination of a frame, a platform pivoted at one end in said frame, a support hinged on one side of said frame and extending in diagonal direction to the other side and engaging under the platform at its forward end to support the same in normal position, means engaging with said hinged support for operating it upon its hinges, and means positioned alongside the cage for operating 85 said means back and forth to raise and lower the hinged platform and the bottom of the car carried thereby, substantially as set forth. 90

9. A hoisting cage for mines comprising a frame, a combination fixed and movable hinged platform, the hinged portion of said platform adapted to carry and support a car with a hinged bottom mounted on tracks on said hinged portion of said platform 100 and adapted to permit the bottom of said car to fall with said portion of the platform when a predetermined level has been reached, and the fixed portion of said platform adapted to hold the body of the car in 105 a horizontal position above said platform when said movable portion of the platform is tripped, substantially as set forth. 95

10. A hoisting cage for mines comprising a platform having fixed portions and a movable portion thereon, a dump car on the trap having a hinged bottom, means on the fixed portions of the platform for supporting the body of the car, and means to raise and lower the trap and the bottom of the car, 110 substantially as set forth. 115

11. A hoisting cage for mines comprising a platform having fixed portions, a trap hinged thereto, a car on the platform having a pivoted bottom portion, supports on 120 the fixed portions of the platform for the body of the car, and means on said supports to hold the car against endwise movement, substantially as set forth.

12. A hoisting cage comprising means 125 for supporting a dump car and also adapted to dump said car, said cage also having means thereon adapted when the dump car is removed to form a non-dumping receptacle on the cage, substantially as set forth. 130

13. A hoisting cage having uprights thereon, leaves pivoted on said uprights and adapted when lowered to form a floor substantially co-extensive with the cage, substantially as set forth.

14. A hoisting cage having uprights thereon, leaves pivoted on said uprights and adapted when lowered to form a floor substantially co-extensive with the cage, and means on the uprights for supporting end members in co-acting relation with said floor, substantially as set forth.

15. A hoisting cage having main and secondary platforms, the main platform comprising a fixed portion and a movable portion, the movable portion adapted to support a dumping car, and movable with the bottom thereof in dumping, and the sec-

ondary platform adapted when the car is removed to act as a non-dumping supporting device for the load, substantially as set forth.

16. A hoisting cage for mines comprising a hinged platform, a dumping car with a hinged bottom thereon and means for tripping the platform to dump the car at a predetermined point, substantially as set forth.

In witness whereof, I have hereunto set my hand and seal at Roundup, Montana, this 31st day of July, A. D. nineteen hundred and twenty.
